FEED MIXING APPARATUS

Clark L. Smith, Leola, Pa.

Application June 27, 1938, Serial No. 216,183

1 Claim. (Cl. 259—23)

This invention relates to feed mixing machines and has for an object to provide a spray pipe for spraying molasses into feed mixtures prior to mixing, such spray pipe being formed in sections 5 so that it may be readily applied to and removed from the feed mixing machine without dismantling the machine.

A further object is to provide a novel spray nozzle having a discharge tip flattened to throw 10 a fan-shaped stream and cover a larger side area than hitherto possible.

With the above and other objects in view the invention consists of certain novel details of construction and combinations of parts hereinafter 5 fully described and claimed, it being understood that various modifications may be resorted to within the scope of the appended claim without departing from the spirit or sacrificing any of the advantages of the invention.

In the accompanying drawing forming part of 10 this specification,

Figure 1 is a longitudinal sectional view, with parts in elevation, of the upper portion of a feed mixing machine having a spray pipe constructed 5 in accordance with the invention applied thereto.

Figure 2 is a plan view of the spray pipe and nozzles shown in Figure 1.

Figure 3 is a longitudinal sectional view of the 10 spray pipe and nozzle taken on the line 3—3 of Figure 2.

Figure 4 is a cross sectional view of the spray 15 pipe and nozzle taken on the line 4—4 of Figure 3.

Referring now to the drawing in which like 20 characters of reference designate similar parts in the various views, 10 designates a mixing chamber of feed mixing apparatus, particularly of apparatus designed to spray molasses into feed preparatory to mixing. 11 designates the feed screw, 12 the casing of the feed screw, 13 the driving shaft for the feed screw, and 14 the motor of such apparatus.

In carrying out the invention I provide an 25 annular spray pipe 15 formed of a plurality of sections, for example two sections 16 and 17 of substantially an arc of 180 degrees in length and having their ends coupled together by couplings 18. By forming the spray pipe in sections the spray pipe may be applied to and removed from the usual position at the top of the initial chamber 10 and below the top of the casing 12 without dismantling the machine.

The spray pipe is provided with a plurality of 30 nozzles each comprising a relatively small tube 19 which extends vertically from the spray pipe 15, the outer end portion of the tube being curved outwardly as shown at 20 and then directed as shown at 21 downwardly. The extreme end of the tube is flattened to provide an elongated discharge tip 22.

In practice, it is found "after drip" is prevented just by the general shape of the nozzle and second by the position of the nozzle in the machine.

The supply pipe 23 for the spray pipe is disposed outside of the mixing chamber 10 and is provided at the upper end with an elbow 24 to which is secured a branch pipe 25 which enters a T-union 26 carried by one of the sections of the spray pipe, as best shown in Figure 1.

In operation the rotating feed screw 11 continuously lifts portions of the dry feed materials vertically in the casing 12 and throws the same off laterally from the top of the casing whereupon the materials will gravitate through the annular space between the casing 12 of the feed screw and the wall 10 of the mixing chamber until it again reaches the bottom of the mixing chamber and is again picked up by the feed screw. Molasses or other liquid materials may be fed into the mixing chamber at the upper end thereof through the pipe 25, annular pipes 16 and 17 and upstanding nozzles 19 so that during the operation of mixing the dry feed materials, the molasses will be introduced thereto to fine sprays at

equally spaced points at about the plane of the top of the feed screw casing 12, thus assuring uniform distribution of the molasses throughout the mass of dry feed. The sections 16 and 17 of the spray apparatus may be disconnected at 20 the couplings 18 and removed from the machine, when the machine is to be used simply for dry mixing and may be set up again in position by simply screwing up the couplings 18 when it is desired to apply molasses to the mixture, without 25 dismantling the machine.

What is claimed is:

In a feed mixing machine having a mixing chamber, an axially disposed upright feed screw in the mixing chamber and a casing for the feed screw open at its upper end; a removable attachment therefor comprising arcuate pipe sections, pipe couplings detachably connecting the ends of the sections together, said sections being disposed concentric with the feed screw casing and disposed adjacent the top of the casing outwardly of the latter within the mixing chamber, said sections being spaced from the casing and from the side wall of said chamber, a supply pipe for liquid connected to one of the sections and projecting exteriorly of the mixing chamber removable through and supported by a wall of the chamber, and a plurality of outlet nozzles rising from the sections, each nozzle comprising a relatively small tube having an upper portion curved 45 outwardly and downwardly and terminating outwardly of and above the sections in approximately the plane of the upper end of the casing. 50
